OIL BURNER APPARATUS

Filed Feb. 3, 1927

UNITED STATES PATENT OFFICE

THOMAS KEENAN, OF BROOKLYN, NEW YORK, ASSIGNOR OF ONE-HALF TO WALTER A. TRAUTH, OF BROOKLYN, NEW YORK

OIL-BURNER APPARATUS

Application filed February 3, 1927. Serial No. 165,520.

This invention relates to oil burners, and particularly to apparatus of this class designed for use in connection with furnaces of various kinds and classes for the generation of heat for transmission through the heating apparatus of which the furnace constitutes a part; and the object of the invention is to provide an apparatus of the class specified comprising a fuel oil storage tank, and means involving control and regulating devices in communication with said tank and positioned between the same and the burner for controlling and regulating the transmission of fuel oil to the burner; a further object being to provide means for siphoning the oil from the storage tank into one of the regulating devices, and further to the provision of means for sounding an alarm when the level of oil in the storage tank assumes a predetermined position; a further object being to provide means for controlling the valve or valves employed in the regulators for shutting off the supply of fuel oil thereto and to the burner, should either one or both of the regulators fail to function; a further object being to provide means for shutting off the transmission of oil from the supply tank to the system in the event of a fire adjacent said tank; a further object being to provide means for discharging fuel oil from one of the regulators employed on the valves controlling the supply of oil to such regulator as fails to perform its function; a still further object being to provide a burner having a flared annular discharge flow, and means for maintaining a level of oil substantially at the base of the flow, and said burner being also provided with a removable lining or facing for the oil chamber of the burner whereby carbon deposits may be removed by the removal of said lining or facing; and with these and other objects in view, the invention consists in an apparatus of the class and for the purpose specified, which is simple in construction, efficient in use, and which is constructed and operated as hereinafter described and claimed.

The invention is fully disclosed in the following specification, of which the accompanying drawing forms a part, in which the

separate parts of my improvement are designated by suitable reference characters in each of the views, and in which:

Fig. 1 is a diagrammatic view of an apparatus made according to my invention, parts of the construction being broken away and shown in section; and,

Fig. 2 is a sectional plan of the oil burner shown in Fig. 1, the section being on the line 2—2 of Fig. 1.

In the drawing, 1 represents a storage tank for fuel oil indicated at 2, the oil being admitted into the tank through a feed tube 3 having a closure cap 4. A vent tube 5 is also coupled with the upper portion of the tank 65 and is exposed to atmosphere. Pivoted in connection with a support 6, arranged in the tank 1 at one end thereof as seen at 7, is a lever 8, the link arm of which carries a float 9. Connected with the short arm is a link 10 which extends upwardly through the tank and into an oil gage 11 having a dial facing 12 in connection with which an indicating finger 13 operates to indicate the amount of oil in the tank, the link 70 10 being coupled with a gear 14 which meshes with a pinion 15 on the shaft of the indicator finger 13, whereby the movement of the float lever 8 will move the finger 13 to relatively indicate the level of oil in the tank 1. A stationary contact 16 is also contained in the gage casing and insulated from and adapted to be engaged by another contact 17 on the gear 14 to complete an electric circuit 18 having a source of electrical supply 80 19 to sound a bell or other signal device 20, a one-wire grounded circuit being employed.

A siphon tube 21 extends to the lower portion of the tank 1 and opens outwardly through the top thereof in a valve casing 22, the spring pressed valve 23 of which is normally held in raised position by a fuse link 24 arranged above the valve casing 21 and exposed to the compartment in which the tank 1 is mounted. Suitable packing 25 is employed 90 around the stem of the valve 23 to prevent the leaking of oil. Coupled with the valve casing 22 is a discharge pipe 26 which opens into the top of a regulator 27 through a valve 28. The regulator 27, in the construction shown, 100

comprises a casing, in the top of which is mounted a diaphragm 29 adapted to actuate a needle valve 30 for controlling the admission of oil into the regulator 27 after passing through the valve 28, the diaphragm 29 forming a chamber 31 in the top of the casing, which chamber is placed in communication with a chamber 32 at the bottom of the casing through a passage 33 extending along one side wall of the casing.

10 The oil passes from the chamber 32 into the float chamber 34 of the casing through a passage controlled by a weighted needle valve 35 normally held in raised position by the weight of the float 36 in the chamber 34 upon a number of detents 37. It will be understood that when the level of oil in the chamber 34 reaches a predetermined position, the float will be raised and the valve 35 allowed to drop 20 by gravity to shut off the supply of oil to the chamber 34. This operation is also facilitated in the engagement of the upper end of the float 36 with the diaphragm 29 to close the valve, thus stopping the admission of oil into 25 the chamber 31.

I also provide the regulator 27 with an overflow safety discharge in the form of a U-tube 38, adjustably supported in an upwardly directed tubular extension 39 of the 30 regulator 27, said U-tube being held in different positions of adjustment by the nut 40 of a stuffing box which also serves to seal the connection between the tube and the extension 39. The extension 39 is placed in communication with the chamber 34 as seen at 41, and a plug 42 is provided at the lower end of the extension to clean out the passage whenever desired. The upper end of the pipe 26 where it extends downwardly into the regulator 27 is provided with a priming plug 26^a whereby the pipe 26 may be filled to provide for the proper siphon functioning of the discharge of the oil from the tank 1.

Coupled with the lower end of the regulator 45 27 and in communication with the chamber 34 thereof is a pipe 43 in which is mounted a strainer 44. This pipe is in communication with a valve casing 45 coupled with a supplemental regulator 46. A valve 47 of the casing 45 is of the quick thread needle type, and the stem of the valve extends through the casing and is provided with a weighted lever 48 held in suspended position by a fusible link 49 whereby in the event of a fire around the 55 regulator 46, the fusible link 49 will be broken, allowing the weighted lever to drop to rotate a valve 47 to move the same into closed position to shut off the supply of fuel oil to the regulator 46.

60 The transmission of oil into the chamber 50 at the lower end of the regulator 46 is controlled by a spring pressed ball valve 51. The transmission of oil from the chamber 50 into the float chamber 52 of the regulator 46 is 65 controlled by a needle valve 53 which is nor-

mally held in raised position by weighted detents 54 pivotally mounted in the upper end of the chamber 52 and engaging a collar 55 on the stem of the valve and moved into closed position in the upward movement of the float 56 which engages and actuates said detents. The valve 53 may also be held in closed position by the weight of the float 56 resting upon a collar 57 at the lower end of the stem of the valve.

70 The valve 53 extends through the upper end of the regulator 46 and is coupled with one end of a lever 58 pivoted to the regulator as seen at 59. Pivoted to the other end of the lever is a rod 60 which extends outwardly through a tubular portion 61 arranged above the spring pressed ball valve 51, and adapted to engage said ball valve to move the same into inoperative position to allow for the transmission of oil into the chamber 50.

75 A discharge pipe 62 is in communication with the chamber 52 and extends to an oil burner 63 which is adapted to be mounted in a furnace of any kind or class and which may be supported upon the grate bars 64 of 80 the furnace. A valve 65 is mounted in the pipe 62 to control the supply of oil to the burner, and said valve is controlled and regulated by a chain 66 coupled with the damper diaphragm or with an automatic thermostatic 85 regulator commonly employed in apparatus of the class under consideration. The valve 65 is adapted to control the volume of oil transmitted to the burner 63. A reduction block 67 is also preferably employed in the 90 pipe 62 between the valve 65 and burner 63 to prevent sudden discharge of oil into the burner, especially in the initial starting of 100 its operation.

95 The burner, in the construction shown, 105 comprises a cylindrical casing 68 having an extension 69 at one side thereof which opens outwardly through the front of the furnace to allow for the transmission of air into the burner, the oil pipe 62 passing through the 110 extension 69. Supported within the casing 68 is an annular oil reservoir 70 with which the pipe 62 couples as seen at 71, and the upper end of this reservoir opens through the top of the burner in a discharge throat having a 115 flared outer wall 72 and flared inner wall 73, the inner wall being of greater height than the outer wall. The air admitted into the casing 68 passes at the inner and outer sides of the reservoir 70 through the chambers 74 and 75 on the inner and outer sides of said reservoir. The air passing through the inner chamber 75 strikes a dome-shaped baffle 76 which encircles the upper edge of the inner flared wall 73, and deflects the air downwardly from said inner wall to the discharge 120 throat of the reservoir 70, while the air passing through the outer chamber 74 is deflected inwardly by an inturned flange 77, after passing through apertures 78. The flame of the 125 130

burner, when in operation, extends upwardly through an annular passage 79 which encircles the baffle 76 within the flange 77.

I also preferably mount within the reservoir 70 of the burner, an annular lining ring or facing member 80 which is U-shaped in form in cross section, and the lower end of which is perforated to allow for the passage of oil into the reservoir. The member 80 is provided with two or more rivets 81 bridging the walls thereof to facilitate the insertion and removal of said member at will. The member 80 is designed to collect whatever carbon may be created in the operation of the burner, and facilitates the removal of such carbon whenever it is desired or deemed necessary. The member 80 is movable through the annular passage 79 as will be understood. It is preferred that the level 20 of oil be maintained on the lines 82 with relation to the burner as well as the regulators 27 and 46, it being understood that said devices will be installed to maintain this level, which is controlled by the float 56 in the regulator 46 and the float 36 in the regulator 27 and also by the safety overflow tube 381.

The operation of my improved apparatus will be readily understood from the foregoing description when taken in connection with 30 the accompanying drawing and the following statement. In the initial starting of the apparatus, it will be understood that oil will be placed in the tubes 21 and the pipe 26 by means of the priming plug 26^a and oil placed in the tank 1. The valve 28 will then be opened to allow for the transmission of oil into the regulators 27 and 46 and thus into the burner until the desired level of oil has been maintained in the burner, at which time the automatic valves in the separate regulators will 40 be actuated to maintain such level of oil until the burner has been ignited or put into operation. A torch or other means is employed for starting the burner operation to provide 45 the necessary heat for the baffle and other surrounding walls of the burner adjacent the discharge 79. When the burner is put into operation and the oil is ignited, as the oil is consumed, the automatic valves of the regulators 50 26 and 46 will operate to replenish the supply of oil to the burner and maintain a substantially fixed level of oil therein at all times during the burner operation. Should, by any chance, one or more of the control valves of 55 the regulator 27 fail to function to shut off the supply of oil, thus causing an overflow in the chamber 34, it will be understood that such overflow of oil will be discharged through the tube 38 positioned slightly above 60 the normal level of oil to be maintained in the chamber 34, and this oil may be transmitted to a suitable container in any desired manner. It will also be understood that the valve 65 will be raised and lowered in the furnace 65 operation to maintain the desired supply of

oil to the burner for regulating the burner operation to produce the required heat in the furnace to maintain the temperature required to heat the rooms or compartments controlled in the heating system of which the furnace 70 constitutes a part.

I also preferably mount in the tubular extension 69 of the burner, a damper valve 69^a for controlling and regulating the admission of air into the burner, and this valve is linked with the damper chain 66 through a lever 69^b and link 69^c. With this construction, it will be seen that as the valve 65 is raised and lowered to control the oil supply to the burner, the valve 69^a is correspondingly operated to 80 control and regulate the air admission to the burner.

It will be understood that while I have shown certain details of construction for carrying my invention into effect, that I am 85 not necessarily limited to these details, nor to the particular arrangement of the devices or mechanisms herein shown and described, and various changes in and modifications of the construction herein set out may be made 90 within the scope of the appended claims without departing from the spirit of my invention or sacrificing its advantages.

The bottom of the burner is also preferably provided with an aperture 63^a which may 95 be closed by a plug 63^b, when desired, the plug may be removed to allow the passage of air or unburnt gases which may collect in the ash-pit portion of the furnace below the grates into and through the passages 74 and 100 75 of the burner.

Having fully described my invention, what I claim as new and desire to secure by Letters Patent, is:—

1. A regulator of the class described comprising a casing, a liquid feed passage traversing the lower end of said casing, a port placing said passage in communication with the chamber within the casing, a valve controlling said port, the stem of said valve projecting through one end of the casing, a float actuated by the level of liquid in the casing and in operative connection with said valve for moving the same into position to close said port when a predetermined level of liquid has 105 been reached in the chamber of said casing, a liquid discharge in communication with said casing at a point below the level of liquid therein, a valve for controlling the admission 110 of liquid into the feed passage, and means in operative connection with the protruding end of said valve stem for controlling the operation of said last named valve whereby the closing of the first named valve will permit of the closing of said second named valve. 115

2. A regulator of the class described comprising a casing, a liquid feed passage traversing the lower end of said casing, a port placing said passage in communication with the chamber within the casing, a valve con- 120

trolling said port, the stem of said valve projecting through one end of the casing, a float actuated by the level of liquid in the casing and in operative connection with said valve for moving the same into position to close said port when a predetermined level of liquid has been reached in the chamber of said casing, a liquid discharge in communication with said casing at a point below the level of liquid therein, a valve for controlling the admission of liquid into the feed passage, means in operative connection with the protruding end of said valve stem for controlling the operation of said last named valve whereby the closing of the first named valve will permit of the closing of said second named valve, and a needle valve outwardly of the second named valve and controlling the feed of liquid to said feed passage and through the second named valve.

3. A regulator of the class described comprising a tubular casing, a chamber in said casing, a discharge in communication with said chamber substantially centrally thereof, an intake port opening into the lower end portion of said chamber, a valve controlling said port, a float in said chamber and in operative connection with said valve to move the stem into closed position in the upward movement of the float in said chamber, a passage in communication with said intake port, a valve controlling said passage, and means involving a plunger rod supported externally of the casing and a lever coupled with said rod and the stem of said first named valve, for controlling the opening and closing of the second named valve.

4. A regulator of the class described comprising a tubular casing, a chamber in said casing, a discharge in communication with said chamber substantially centrally thereof, an intake port opening into the lower end portion of said chamber, a valve controlling said port, a float in said chamber and in operative connection with said valve to move the stem into closed position in the upward movement of the float in said chamber, a passage in communication with said intake port, a valve controlling said passage, means involving a plunger rod supported externally of the casing and a lever coupled with said rod and the stem of said first named valve for controlling the opening and closing of the second named valve, and a needle valve for regulating the flow of fuel to the second named valve and said passage.

5. A regulator of the class described comprising a chamber into and through which a liquid is adapted to pass, an inlet passage for supplying liquid to said chamber, a discharge communicating with the central portion of the chamber, means involving two independent valves, one arranged within the chamber and the other externally thereof for controlling the supply of liquid to said chamber

through said intake passage, a float disposed in said chamber and actuated by the level of liquid therein and in operative connection with said valves to control the operation thereof, and means outwardly of said chamber for coupling said valves to transmit relative movement thereto in the actuation of said float.

In testimony that I claim the foregoing as my invention I have signed my name this 28th day of January, 1927.

THOMAS KEENAN.
